UNITED STATES PATENT OFFICE.

GEORGE H. EVERSON, OF PITTSBURG, PENNSYLVANIA.

MANUFACTURE OF COMPOUND TUBES.

No. 904,189.

Specification of Letters Patent.

Patented Nov. 17, 1908.

Application filed April 7, 1906. Serial No. 310,404.

To all whom it may concern:

Be it known that I, GEORGE H. EVERSON, a citizen of the United States, residing at Pittsburgh, in the county of Allegheny and State of Pennsylvania, have invented certain new and useful Improvements in the Manufacture of Compound Tubes, of which the following is a specification, reference being had therein to the accompanying drawing.

10 Heretofore in the manufacture of compound tubes, that is—tubes lined with brass, copper, aluminum, and other metals, it has been necessary to have an outer steel or iron tube of larger diameter than the same tube 15 when finished in order to receive the inner tube, the combined tubes being then rolled down to standard commercial size. In this practice, difficulty is experienced in obtaining tubes of proper initial size as the sizes 20 required are just a little larger than the standards followed by tube manufacturers.

One object of the invention is to obviate this difficulty by using tubes of standard size, the tubes being expanded in the compound- 25 ing operation, and then rolled down in the finishing process to standard size.

A further object is to provide an improved method of manipulating the tubes in the process of uniting them, whereby their union 30 is made more positive and the adherence of one to the other more secure than heretofore.

In the accompanying drawing, Figures 1, 2, 3 and 4 are views illustrating the several steps of the improved method.

35 Referring to the drawing, 2 designates a mandrel formed preferably of high carbon steel, and hence so hard that it need not be tempered to withstand the work. One end of this mandrel is reduced and threaded, as 40 indicated at 3, to receive the detachable bulb-shaped expander 4 and securing nut 3'. The opposite end of the mandrel is formed with the usual grip-hold 2'. The mandrel is heated by any suitable means and a relatively 45 short and thick tubular billet 5 of brass, copper, aluminum or other lining metal is placed thereon and rolled down to form the inner tube or lining 6. With the mandrel at a temperature of about 600 degrees Fahrenheit, this rolling down and elongating process is greatly facilitated, as thereby the lining material is heated and given greater ductility. And furthermore, with the inner tube thus heated it expands more readily 55 within the outer tube as required by a subsequent step of the process. After the inner

tube has been rolled down to proper gage, the mandrel with the inner tube thereon is inserted within outer tube 7, the latter being of standard size. Then with the expander 4 60 in position, the assembled tubes and mandrel are arranged in a draw-bench, 8 being the draw head thereof, and the mandrel is withdrawn, as shown in Fig. 3. When being thus withdrawn, bulb 4 expands the inner 65 tube, causing it to tightly fit the outer tube, and the bulb is of such size as, at the same time, to appreciably expand the outer tube 7, thus making its diameter slightly greater than standard. This slight enlargement is 70 eliminated and the compound tube again reduced to standard size by the last step of the process which consists in inserting a finishing mandrel 9, and rolling the compound tube thereon for the purpose of insuring the 75 union between the outer and inner tubes at all points. The finishing mandrel is preferably heated, a desirable method of heating being that described in Letters Patent granted me June 3, 1902, No. 701,693. With the 80 finishing mandrel heated, the inner tube is not chilled, and the contraction of the mandrel when cooling is sufficient to loosen it and permit of its ready removal.

I claim:—

85

1. The method of manufacturing compound tubes consisting in expanding the inner tube into tight engagement with the outer tube and at the same time expanding the outer tube, and then contracting the 90 united and expanded tubes.

2. The method of manufacturing compound tubes consisting in rolling the inner tube on a mandrel, placing the inner tube and mandrel within the outer tube, remov- 95 ing the mandrel and at the same time expanding the inner tube into engagement with the outer tube, and then rolling the tubes.

3. The method of manufacturing com- 100 pound tubes consisting in rolling the inner tube on a heated mandrel, placing the heated mandrel and the rolled inner tube within the outer tube, removing the mandrel and expanding the inner tube into tight engage- 105 ment with the outer tube, and rolling the united tubes.

4. The method of manufacturing com- 110 pound tubes consisting in rolling the inner tube on a heated mandrel, placing the heated mandrel and the inner tube within the outer tube, removing the mandrel, expanding the

inner tube into tight engagement with the outer tube and at the same time expanding the outer tube, and then contracting the united tubes.

5. The method of manufacturing compound tubes consisting in rolling the inner tube on a heated mandrel, placing the mandrel and inner tube within the outer tube, removing the mandrel and expanding the inner tube in tight engagement with the outer

tube and at the same time expanding the outer tube, and then rolling the united tubes on a heated mandrel for contracting the same.

In testimony whereof I affix my signature 15
in presence of two witnesses.

GEORGE H. EVERSON.
